United States Patent Office

Des. 233,498
Patented Nov. 5, 1974

233,498

DRESSER OR THE LIKE

Huey T. Keller, High Point, N.C., assignor to The Vaughan Furniture Company, Inc., Galax, Va.

Filed Jan. 17, 1973, Ser. No. 324,555

Term of patent 14 years

Int. Cl. D6—04

U.S. Cl. D6—154

FIG. 1

FIG. 3

FIG. 2

FIG. 1 is a front elevational view of my furniture or the like showing my new design;

FIG. 2 is an end elevational view of the same, the opposite end being substantially a mirror image of that shown; and

FIG. 3 is a top plan view of the same.

I claim:

The ornamental design for a dresser or the like, as shown and described.
